Charles L. Wright

UNITED STATES PATENT OFFICE.

LAWRENCE J. WIDNESS, OF BROOKLYN, NEW YORK.

TOY.

1,389,802.

Specification of Letters Patent. Patented Sept. 6, 1921.

Application filed January 27, 1921. Serial No. 440,262.

To all whom it may concern:

Be it known that I, LAWRENCE J. WIDNESS, a citizen of the United States, and a resident of Brooklyn, in the county of Kings and State 5 of New York, have invented certain new and useful Improvements in Toys, of which the following is a specification.

The principal object of this invention is to produce a toy carrying one or more figures 10 or objects so mounted as to be capable of continuous limited lively movement for a considerable period of time.

A further object is in the provision of a toy which, due to the rapid motion imparted 15 to the object carried presents the illusion of its members moving in rhythm and symmetry.

Another object is to provide a device of 20 highly amusing and interesting type, easily put into actuation by a mere touch, durable in its nature and which can be constructed at a moderate expense.

These and other like objects are attained 25 by the novel construction, combination and arrangement of parts hereinafter described and shown in the accompanying drawings forming a material part of this disclosure, and in which:

Figure 1 is a perspective view showing the 30 figure in broken lines in another position.

Fig. 2 is a transverse sectional view taken on line 2—2 of Fig. 1.

Stated in general terms, the invention is comprised of a base having an overlying 35 platform and upright wall or back-ground secured to it.

Rigidly fixed in the base is a support, such as a thin wire, the same extending upward 40 behind and clear of the upright, having included in its length several helical coils or spring elements, and then bent to form a loop passing freely over the wall, down to a point approximately at its center where it is secured to any preferred image.

Such article or object may be, as shown, 45 a representation of the well known typical character Charlie Chaplin, whose absurd, grotesque and ludicrous movements are faithfully portrayed.

So too, the figure of an animal as a dog 50 or horse is caused to simulate running or galloping, the limbs apparently moving with reference to the body although in reality they do not.

Due to the peculiar mounting, figures in 55 the image of sparring partners or boxers are

made to apparently assume different postures and movements depictive of the actions of real actors or gymnasts.

Referring now more particularly to the 60 drawings, the numeral 10 designates a relatively heavy base, preferably a wooden plate or block in the form of a parallelogram, the same having secured upon its upper surface a platform 11 representing the flooring of a 65 stage, this being a level rectangle, its length exceeding the width as shown.

Secured to the rear edge of the base 10 is an upright wall or plate 12 extending coincident with the platform 11 and to a considerable height above it, this wall being 70 preferably finished on its front surface to represent suitable scenery used as a background.

Rigidly fixed in the base 10, at the center 75 of its rear edge, is the end of a wire 14, made of resilient material of an approved size, the same extending rearwardly and then upwardly to the helix 15 formed in the wire, which is then continued as at 16 vertically, forming one element of an arcuate loop 17 disposed above the upper edge of the wall 12, the other member 18 of the loop extending down in front of the wall to a point below the center of its height, where it is 85 turned outwardly at a right angle to the front forming an element 19 extending substantially to the center of the platform 11.

Fixed to the end of the wire element 19 is a platform 21 supporting the lower end of 90 an object, as the image 20 representing the person or thing constituting the main element of the toy.

This object is of rigid construction, that is, the parts representing the limbs and other 95 portions are fixed with respect to the body so as to move in unity, and the article is preferably of considerable weight.

It will be seen and understood that the 100 loop elements 16 to 18 are at all times clear of the wall 12 and due to their length, together with that of the coil 15 and other elements integrally formed of the wire, the object is carried at the extreme end of a long and highly resilient support, in fact being 105 floatingly mounted to move universally in a plane approximately parallel to the background 12.

For instance, if the loop 17 be lightly struck, it is caused to vibrate, imparting a 110 similar but increased vibration to the article which, due to the inertia of its weight, sets

up within itself a gyrating effect about the axis of the wire 19, the upper extremities moving obviously to a greater extent than the center of the article due to the torsional resistance of the support.

If the object be struck at about its center, sidewise, such movement will continue like a pendulum until inertia overcomes its effect.

Should the blow be delivered to the extremities, as the head or feet, a combined axial twisting and swaying action is set up, while if the blow be vertical a dancing effect is obtained combining an up and down, and tilting movement.

15 From the foregoing it will be seen that a wide range of action may be given the image used as the main feature of the device and that due to the extreme length and resiliency of its support, such action will be maintained for a very considerable period of time.

Notwithstanding the simplicity of construction and operation of this toy it affords a highly attractive form of amusement and fully complies with the several objects set forth.

While certain preferred embodiments of this device have been shown and described, it will be understood that changes in the form, arrangements, proportions, sizes and details thereof may be made without departing from the scope of the invention as defined in the appended claims.

Having thus described my invention, what I desire to secure by Letters Patent and claim, is:—

1. A toy comprising a base, a plate representing a background at the rear of said base; an image, a single wire support for

said image, extending over said plate and secured in the rear edge of said base, and a 40 single helix in said wire, said wire permitting free action of said image over the base.

2. A toy comprising a base, a plate representing a background at the rear of said base; an image, a spring wire fixed in the 45 rear edge of said base supporting said image at the bottom thereof, said wire containing a loop extending over said plate above said image, and a single vertical helix formed in said wire adjacent said base, said spring wire 50 permitting vertical and lateral movement of said image.

3. A toy comprising a base, a level platform thereover, a vertical wall at the rear of said platform, an image disposed centrally over said platform, and a single wire fixed in the rear edge of said base, said wire having a loop extending over the upper edge of said wall and bent outward to support said image in an essentially universal 60 manner.

4. A toy comprising a base, a level platform thereover, a vertical wall at the rear of said platform, an image disposed centrally over said platform, a single wire fixed in 65 said base, said wire having a loop extending over the edge of said wall, a horizontal element extending from the inner end of the loop attached to said image and a helix formed in the outer element of said loop, 70 said wire acting as a torsional support to said image.

In testimony whereof I have signed my name to this specification.

LAWRENCE J. WIDNESS.
